CLAIM

The ornamental design for a cell phone case, as shown and described.

DESCRIPTION

FIG. 1 is a top perspective view of a cell phone case in accordance with a current invention.

FIG. 2 is a bottom perspective view thereof.

FIG. 3 is a top plan view thereof.

FIG. 4 is a bottom plan view thereof.

FIG. 5 is a side elevation view thereof; and,

FIG. 6 is an end elevation view thereof.

The broken lines illustrate the environment in which the cell phone case is used and form no part of the claimed design.
